NEWS AND ADVERTISING INFORMATION DISPLAY SIGN

James H. Firmin, Lake San Marcos, Calif., assignor to Capsule Communications, Inc., San Marcos, Calif.

Filed June 30, 1972, Ser. No. 267,918

Term of patent 14 years

Int. Cl. D20—03
U.S. Cl. D96—12 R

FIG. 2

FIG. 1

FIG. 1 is a bottom, left side and front perspective view of a news and advertising information display sign showing my new design, the top being plain and unornamented;

FIG. 2 is a right side elevational view thereof;

FIG. 3 is a rear elevational view thereof.

I claim:

The ornamental design for a news and advertising information display sign, substantially as shown and described.
